UNITED STATES PATENT OFFICE

100,141

DESIGN FOR A TABLE OR THE LIKE

Frederick W. Worth, Chicago, Ill.

Application January 31, 1936, Serial No. 60,914

Term of patent 3½ years

To all whom it may concern:

Be it known that I, Frederick W. Worth, a citizen of the Republic of Germany, residing at Chicago, in the county of Cook and State of Illinois, have invented a new, original, and ornamental Design for a Table or the like, of which the following is a specification, reference being had to the accompanying drawing forming a part thereof.

The dominant features of my design reside in the provision of a table or the like having shelves formed in the end portions and a slideable drawer-like compartment in the side portion of the table.

I claim:

The ornamental design for a table or the like, as shown and described.

In witness whereof, I hereunto subscribe my name this 25 day of January, 1936.

FREDERICK W. WORTH.
